UNITED STATES PATENT OFFICE.

BONIFACE A. GRASBERGER, OF RICHMOND, VIRGINIA.

DRINKING-CUP.

1,186,184.

Specification of Letters Patent.

Patented June 6, 1916.

Application filed January 27, 1915. Serial No. 4,704.

To all whom it may concern:

Be it known that I, BONIFACE A. GRASBERGER, a citizen of the United States, residing at Richmond, in the county of Henrico and State of Virginia, have invented certain new and useful Improvements in Drinking-Cups, of which the following is a specification.

This invention contemplates an improved 10 drinking cup and has as its primary object to provide a device of this character employing a construction especially adapted to the use of paper or other fibrous material in the formation of the cup.

15 The invention has as a further object in this connection to provide an improved cup having as its salient feature, simplicity of construction, while at the same time, a thoroughly efficient article will be produced.

20 A still further object of the invention is to provide a cup so constructed that the elements thereof may be readily formed, and wherein the individual elements of the cup will be such, that but a minimum amount of 25 stock will be wasted in forming the blanks providing the said elements, from the stock.

Other and incidental objects will appear 30 as the description proceeds and in the drawings wherein I have illustrated the preferred embodiment of the invention and wherein similar reference characters designate corresponding parts throughout the several views,

Figure 1 is a perspective view of my improved cup. Fig. 2 is a fragmentary sectional view illustrating the construction and mounting of the bottom wall of the cup. Fig. 3 is a view on a slightly reduced scale showing the blank from which the side wall 40 of the cup is formed. Fig. 4 is a detail sectional view illustrating the manner in which the side wall of the bottom of the cup is plaited or crimped to fit within the body of the cup. Fig. 5 is a fragmentary sectional 45 view disclosing the arrangement of the adhesive receiving channels formed in the side wall of the bottom of the cup, and Fig. 6 is a fragmentary sectional view showing a slight modification in the mounting of the bottom 50 of the cup.

In carrying out my invention, I employ a blank 10 which as best shown in Fig. 3 of the drawings, is formed from a single piece of material. The blank 10 may be struck 55 from a piece of preferably paraffin paper stock, although Manila paper of suitable

character could also be employed, where desired.

It will be observed upon reference to Fig. 3 that the end edges of the blank 10 are straight and uninterrupted and converge toward one side edge of the blank upon radial lines. The side edges of the blank are also uninterrupted and are each defined by an arc having a center common to both. Formed in the blank 10 adjacent one side thereof is an arcuate channel which is preferably pressed into the stock to provide a longitudinally extending rib 11.

The blank thus formed is rolled longitudinally to form the substantially frusto conical body portion 12 of the cup, the end margins of the blank being arranged in overlapping relation as best shown in Fig. 1 of the drawings and being adhesively connected to each other or secured together in any suitable manner. It will be noted that the rib 11 is thus disposed adjacent the upper or larger end of the body portion of the cup, providing not only, a reinforcing rib, 80 but an annular radially extending shoulder on the side wall of the cup adapted to engage the upper edge of an adjacent cup when several of the cups are nested.

Particular attention is now directed to the fact that throughout the overlapping portions of the side wall of the cup, the shoulder provided by the rib 11 upon the inwardly disposed overlapping portion, is adapted to engage within the channel 90 formed by pressing the rib outwardly, as previously referred to, of the outwardly disposed overlapping portion. As will be clear, such engagement of the shoulder within the channel at the point mentioned will effectually counteract any tendency of the overlapping ends of the side wall to shift relative to each other in a vertical plane, and will coact with the adhesive securing the overlapping ends together, for providing 100 an efficient and rigid structure. The bottom 13 of the cup is also, as in the case of the side wall, preferably formed from a blank which, however, is not shown, and which may be constructed from a piece of stock 105 similar to that employed in forming the body of the cup. As will be readily seen, upon reference to Fig. 2 of the drawings, the blank providing the bottom wall 13 previous to being bent as shown therein, is substantially circular, and adjacent its periphery, is bent laterally to provide an an-

nular side wall 14. When the blank is thus folded, it will be noted that the bottom of the cup is substantially frusto conical in contour. Formed in the upper free margin 5 of the side wall 14 are superposed series of circumferentially extending reversely presented inner and outer plaits designated 15 and 16 respectively, which extend vertically of the said side wall, and, as best shown in 10 Fig. 2 of the drawings, taper in width as they approach the bottom wall 13, the individual plaits of each series being arranged in staggered relation to adjacent plaits of the other series.

15 In this connection, particular attention is directed to Fig. 4 of the drawings wherein the construction and arrangement of the plaits 15 and 16 are particularly shown. It will be noted that each plait of the inner 20 series of plaits 15 has its longitudinal side walls arranged in spaced relation to the confronting ends of adjacent plaits of the said series and merges, at its sides, with the sides of adjacent superposed plaits of the outer 25 series of plaits 16. As in the case of the inner series of plaits 15, the individual plaits of the outer series of plaits 16 are also preferably each arranged with their sides disposed in spaced relation to the confronting ends of adjacent plaits of the said 30 outer series. By this arrangement, the wall 14 adjacent the upper margin thereof is made expansible whereby the circumference of the said wall, throughout the greater 35 portion of its length may be either increased or diminished and attention is called to the fact that each individual plait of the inner series of plaits 16 in connection with the confronting ends of adjacent superposed 40 plaits of the outer series of plaits 16, provide vertically arranged channels 17 tapering in width toward the bottom wall 13.

45 As best shown in Fig. 2 of the drawings, the series of plaits 15 and 16 respectively merge at the lower extremities thereof, into the inner and outer surfaces of the side wall 14, to provide, upon the outer face of the cup and adjacent the bottom wall 13, an annular substantially smooth and uninterrupted bearing surface 18.

55 The bottom of the cup is preferably arranged within the smaller end of the body portion 12 as shown in Fig. 2 of the drawings and the outside diameter of the bottom wall 13 is such that the bottom of the cup will fit snugly within the side wall thereof to frictionally engage the inner face of said wall, the bottom wall 13 being preferably arranged in a plane with the bottom edges 60 of the body of the cup, with the side wall 14 flaring outwardly to seat against the said side wall adjacent the lower margin thereof.

65 Particular attention is now directed to the fact that the bearing surface 18 of the side wall 14 will have uninterrupted engagement

with the inner face of the side wall of the cup and will thus close the channels 17 at their lower ends. It is further to be noted that the inner and outer series of plaits 15 and 16 may be expanded or contracted so 70 that the wall 14 will yieldably engage against the side wall of the cup to thus provide an effective closure. Previous to so disposing the bottom of the cup within the body portion thereof, the outer faces of the outwardly disposed series of plaits 16, are coated with paste or other suitable adhesive while the channels 17 are preferably entirely filled with such adhesive. Thus, when the bottom of the cup is applied as just 80 above described, the adhesive within the channels 17 will be held therein through the engagement of the bearing surface 18 with the said side wall of the cup, the said adhesive within the channels 17 in the finished cup, thus permanently closing the said channels and effectively sealing the side wall 14 to the side wall of the cup. 85

90 Normally, the side wall 14 adjacent the upper free margin thereof will be of a diameter greater than the diameter of the cup taken in a plane with the upper edge of the wall 14. Consequently, when the bottom of the cup is disposed in position, the spaced confronting edges of the inner series of 95 plaits will be moved toward each other, and this will also occur in connection with the outer series of plaits 16. The wall 14 will thus adjust itself to the diameter of the cup in a plane passing through the said wall 100 and will therefore, being thus expansible, compensate for any unevennesses in the side wall of the cup adjacent the lower end thereof.

105 When the outer series of plaits 16 are thus moved toward each other as just above described, the width of the channels will be correspondingly decreased so that the adhesive contained within the said channels will be forced outwardly against the contiguous portions of the inner face of the side wall of the cup to thus effectually secure the bottom wall in position, it being remembered, as above stated, that the outer 110 faces of the outer series of plaits 16 are also 115 preferably covered with adhesive to thus become secured to the said side wall. This is considered to be an important feature of advantage in the present invention since the adhesive contained within the channels 120 14 will automatically be brought into contact with the side wall of the cup upon the insertion of the bottom of the cup within the body thereof.

125 In Fig. 5 of the drawings, I have illustrated a slight modification of the invention which consists in reversing the disposition of the bottom 13 of the cup from that shown in Fig. 2. Otherwise, the elements of the cup are constructed in the same manner as 130

above described with reference to the preferred form of the invention and will also coact in a similar manner to produce the finished article.

5 It will therefore be seen that I provide an exceedingly simple and desirable construction wherein to produce the cup, but two separate elements are employed which are so formed and arranged as to provide a

10 thoroughly efficient article of manufacture.

Having thus described my invention, what I claim and desire to secure by Letters Patent is:—

An article of the character described including a body portion, and a closure fitted within the body portion and provided with a securing wall having one margin thereof plaited to form a series of adhesive receiv-

ing channels confronting the wall of the body portion and each having sides tapering uniformly along straight lines diverging toward the free edge of said wall with the said channels opening at their outer extremities upon said edge, the opposite margin of the said wall of the closure being provided with an uninterrupted bearing surface seating against the wall of the body portion to close the said channels at their inner extremities.

20 In testimony whereof I affix my signature 25 in presence of two witnesses.

BONIFACE A. GRASBERGER. [L. s.]
